LOCK SWITCH

Filed July 21, 1927

UNITED STATES PATENT OFFICE

ALBERT E. KOFFER, OF DAYTON, OHIO, ASSIGNOR TO DELCO-REMY CORPORATION, OF DAYTON, OHIO, A CORPORATION OF DELAWARE

LOCK SWITCH

Application filed July 21, 1927. Serial No. 207,335.

This invention relates to electric switches having an operating member movable into circuit closing position only by the use of a key and movable into circuit open position 5 with or without the use of a key and automatically locked in open position.

One object of the present invention is to provide a small compact structure including an electrical switch and a lock therefor which 10 structure is particularly adapted to be housed within a tubular metallic member preferably of hard metal which encloses the switch and if desired the wires which lead from the switch to some piece of apparatus controlled 15 by it.

More particularly it is an object to provide for the control of the ignition circuit of an automobile by means of a small compact cylindrical structure comprising an electric switch and lock therefor, the structure being adapted to be located within a tubular metallic housing located within convenient 20 reach of the driver. The metallic housing may be associated with a hard metal tube 25 for enclosing the wires leading from the switch to the ignition apparatus under the hood of the automobile.

Further objects and advantages of the present invention will be apparent from the following description, reference being had to the accompanying drawings, wherein a preferred form of embodiment of the present invention is clearly shown.

In the drawings:

35 Fig. 1 is a front view of a lock and switch structure embodying the present invention.

Fig. 2 is a sectional view on the line 2—2 of Fig. 1.

Fig. 3 is a rear view looking in the direction of the arrow 3 in Fig. 2.

Fig. 4 is a side view looking in the direction of the arrow 4 in Fig. 1.

Fig. 5 is a view similar to Fig. 4 with a 45 part of the casing broken away to show certain parts in position for permitting movement of the switch controlling member to switch closing position.

Fig. 6 is a view similar to Fig. 5 showing the position of the parts after the switch is 50 in closed position.

Fig. 7 is a view partly in section on the line 7—7 of Fig. 3.

Fig. 8 is a view on the line 8—8 of Fig. 4 showing the structure with the back of the switch removed.

55

Fig. 9 is a view similar to Fig. 8 but showing the switch case in cross section, the section being taken principally on the line 9—9 of Fig. 4.

The switch and lock structure is housed 60 by a cylindrical, tubular metallic case 20 which is closed at one end by a non-conducting cover 21 attached to the case 20 by screws 22. Angular contact brackets 23 are attached by rivets 24 to the outside of the cover 21. 65 Each bracket 23 supports by a rivet 25 a leaf spring conductor 26 and each bracket is threadedly engaged by a terminal screw 27. The conductors 26 extend through a square hole 28 in the cover 21, and within the case 70 20 the conductors 26 are provided with contact portions 29 which are biased into engagement with each other due to the resiliency of the conductors 26. The contacts 29 are maintained separated by a non-conducting plate 30 attached by rivets 31 to a metal bracket 32 which is attached by a screw 33 to a cylindrical switch controlling member 34 which is longitudinally movable within the housing 20. The bracket 32 is 80 provided with a finger 35 extending into an elongated aperture 36 provided in the side of the case 20 as shown in Fig. 4. Thus the controller 34 is prevented from turning relative to the case 20 but may be moved longitudinally thereby.

85 The controller 34 is maintained in position for separating the conductors 26 as shown in Figs. 2 and 4 by a latch 40 which is pivoted upon a stud 41 attached to the case 20 and which is provided with a hook portion 42 which engages the extension 35 of the bracket 32. The latch 40 is yieldingly maintained in this position by spring 43 having a portion coiled about the stud 31 and having one end 44 thereof extending into a notch 45 of the stud 41 and having the other end 46 thereof bent over the latch 40. The spring 43 is biased to move the latch 40 in a clockwise direction as viewed in Figs. 4, 5 and 6. Thus 90 95 100

the latch 42 by its engagement with the finger 35 of the bracket 32 resists movement of the controller 34 to the left as viewed in Fig. 2 or to the right as viewed in Figs. 4, 5 and 6. 5 The latch 42 maintains in a state of compression a spring 50 having one end received by recess 51 in the cover 21 and the other end received by cup shaped member 52 bearing against a key shaft 53 which is carried by the controller 34. The member 52 is retained in position by attaching it to the end of the key shaft 53 by screw pins 54 passing through holes of the flat end member 52 and driven into plain holes drilled into the end of the 10 key shaft 53.

Controller 34 and key shaft 53 constitute the usual elements of a pin-tumbler lock in which the shaft 53 can be turned relative to the member 34 only by inserting the proper key 55 into a key slot provided by the shaft 53. Movement of the shaft 53 relative to the controller 34 is limited by pins 56 and 57 which obstructs the movement of pin 58 attached to the key shaft 53. When the shaft 53 20 is turned in a counter-clockwise direction as viewed in Fig. 8 a pin 60 carried by it will engage a lug 61 provided by the latch 40 and will cause the latch 40 to move from the position shown in Fig. 4 to that shown in Fig. 5. 25 After the hook 42 is free of the finger 35 of the bracket 32 the finger 35 and hence the controller 34 are free to move from the position shown in Fig. 5 to the position shown in Fig. 6. The movement of these parts is produced 30 by the spring 50 which causes the controller 34 to continue to move to the right until the finger 35 strikes the right hand edge of the slot 36. After this movement has taken place 35 the non-conducting block 30 will be retracted from the conductors 26 to allow their contact 40 portions 29 to engage. Under these conditions the switch will be closed by the completion of the circuit between its terminal 45 brackets 23. The key 55 may be removed if desired after the key shaft has been turned to key-removal position. Whether or not the key remains in the lock the switch may be moved to open position and will be automatically locked in this position by pushing the controller 34 toward the housing 20. In 50 either instance, the pin 60 which is mounted on the key shaft, is moved to the initial position upon turning of the key shaft to key removal position. During this movement of the controller 34 the finger 35 will ride under the latch 40 until it is located opposite the notch 40a thereof, whereupon the spring 46 will be released to move the latch 40 into the position shown in Fig. 4 in which the hook 55 55 60 65 70 75 80 85 90 95 100 105 110 115 120 125 130 135 140 145 150 155 160 165 170 175 180 185 190 195 200 205 210 215 220 225 230 235 240 causing the electric circuit to be interrupted across the contacts is a non-conducting plate attached to a metal bracket attached to the inner end of the controller and provided with an arm extending into a longitudinal slot in the side wall of the case, said arm also providing the latch finger engageable with the latch plate.

8. A lock switch comprising a cylindrical, tubular case, a non-conducting cover for one end of the case and carrying terminals on the outside thereof and spring conductors located within the case, a cylindrical controller slideable within the bore of the case and carrying a bracket having a laterally extending arm projecting into a longitudinal slot in the side wall of the case, said arm providing a latch finger, said bracket carrying a non-conducting plate which is movable between the conductors to separate them or to permit them to complete an electric circuit, a latch pivoted upon the case and rotatable on an axis transverse to the case and having a hook engageable with the latch finger, a spring urging the latch toward the latch finger, a key controlled shaft carried by the controller and carrying means for tripping the latch, and a spring located between the controller and the end cover for forcing the former away from the latter when the latch is tripped.

In testimony whereof I hereto affix my signature.

ALBERT E. KOFFER.
